UNITED STATES PATENT OFFICE.

JOHN G. JONES, OF ROCHESTER, NEW YORK, ASSIGNOR TO EASTMAN KODAK COMPANY, OF ROCHESTER, NEW YORK, A CORPORATION OF NEW YORK.

PHOTOGRAPHIC CARTRIDGE.

Application filed July 25, 1921. Serial No. 487,449.

To all whom it may concern:

Be it known that I, JOHN G. JONES, a citizen of the United States of America, residing at Rochester, in the county of Monroe 5 and State of New York, have invented certain new and useful Improvements in Photographic Cartridges, of which the following is a full, clear, and exact specification.

This invention relates to photographic 10 roll film cartridges of the type commonly used in cameras and comprising a roll film and protective paper therefor.

More particularly this invention has for 15 its object the elimination of the fault commonly known as edge fog which results from the undesired leaking of light into the margin or border of a roll film. In my co-pending application Serial No. 487,447, filed July 25, 1921, I have disclosed the use of a protective paper having portions of varying 20 flexibility which permit the paper, even though wider than the distance between the flanges, to buckle or be compressed upon itself, thus forming light locks at the ends 25 of the spool.

This application relates to certain modifications of this principle, and more particularly to protective paper in which the greater 30 flexibility is obtained by serrating the edges of the protective material.

It is obvious that modifications embodying 35 the invention as defined in the appended claims are possible, and I have described certain of these which are shown in the figures in the drawing, to which reference will now be made. Those parts which are the same in the various figures bear the same 40 reference characters in each.

Fig. 1 is a perspective view of a partially 45 unwound film cartridge, the leader strip being broken away;

Fig. 2 is an elevation showing the film and 50 backing paper entirely unwound from the spool;

Fig. 3 is an elevation showing the film with lead strips only;

Fig. 4 is an elevation of one end of a modified form of backing paper;

Fig. 5 is an elevation of one end of another 55 modified form of protective paper;

Fig. 6 is a fragmentary view showing a section of protective paper with a modified form of edge;

It is to be understood that the figures are 60 not drawn to scale, but are so dimensioned

as to bring out particularly the features of the invention.

Upon a film spool of ordinary character comprising a core A and metallic end flanges B are interwound a strip of film F and backing paper 1 to which the film is attached by the usual sticker band S. The backing paper 1 is serrated at its edges 2, preferably throughout its length and the greatest total width of the backing paper is greater than 65 the distance between the flanges B of the spool upon which it is wound.

It is to be understood that the backing paper extends the full length of the film and beyond it at each end to form safety leader 70 strips, as indicated at 3 in Fig. 2. The rear end of the film also has a sticker band S' which is not, however, ordinarily attached to the backing paper when the cartridge is 75 sold.

The serrations may be regular, as indicated in Fig. 1, each one having the same depth and width, or they may be, and preferably are, somewhat irregular, as indicated at 4 in Fig. 2, the tops of the serrations on 80 each edge lying in a common line, but the distance from top to top being variable. I find this irregular arrangement preferable, because there is less likelihood of a series of serrations lying directly one over the other, 85 so as to make a kind of channel down the edge of the paper between it and the flange.

Instead of interwinding the protective material and the paper, as is done when a backing paper, such as is shown in Figs. 1 and 2 90 is used, lead strips only may be used with the film, this being shown in Fig. 3, where the film is attached by stickers S to the lead strips 5 having their edges serrated at 4 95 similar to the edges shown in Fig. 2.

If desired, however, a backing paper may be used which extends the full length of the film and may be interwound therewith, in which the intermediate portion 6 which lies opposite to the film in use is narrower than the end strips 7, the latter only being serrated as shown in Fig. 4. This figure also shows an extremely irregular serration 8 which may be employed. The protective strip may moreover have the serrations along 100 one edge only, as indicated at 9 in Fig. 5, the other edge 10 being straight. In all of the forms described the end of the lead strip is tapered, as indicated at 11, as is usual.

While in the forms of edges above de- 110

scribed, the backing paper is of uniform thickness, the flexibility of the marginal portion being obtained only by the decrease of volume obtained by the indentations, the 5 greater flexibility and decrease in volume may be obtained by combining with the serrated edge a thinned, chamfered, or beveled edge, as indicated in Fig. 6. In this the protective paper 12 gradually decreases at its 10 edge from its greatest thickness at 13 in a gradual bevel, as indicated at 14 to an irregular edge, as indicated at 15, the decrease in volume and the increase in flexibility of the margin being obtained both by the beveling and by the serration thereof.

It is obvious that in each of the forms described there is a band of coiled film around the outside of which is a band of protective material, at least one edge of which is serrated. The buckling or friction of the outer points of the serrations under slight pressure will form a light tight lock between the edges of the paper and the inner surfaces of the flanges.

25 While I do not limit myself as regards the dimensions, shape and uniformity of the serrations, I find that satisfactory results are obtained if the total width of the backing paper is about .04" wider than the distance between the flanges, and the serrations made of a depth of about .03" and an average distance between the tops of the serrations of about .05", it being understood that the above dimensions are merely illustrative examples, the dimensions varying more or less with the size of the cartridge, the above data being for paper cut about $3\frac{1}{2}$ " wide.

Claims:

- 40 1. An article of manufacture, comprising a spool with end flanges, a band of photographic film wound thereon, sheet protective material attached to the film and constituting end strips wound on the spools inside 45 the film and outside thereof, at least one side margin of each end strip being serrated and the width of the end strips being greater than the distance between the flanges.

2. An article of manufacture, comprising a roll of sensitized material, a support therefor comprising spaced end flanges, and a strip of protective material with a serrated side edge wound around said sensitive material, said strip being wider than the distance between said flanges. 50

3. An article of manufacture, comprising a spool with end flanges, sensitized material and protective paper interwound thereon, the paper having serrated side edges and being of uniform thickness and wider than the distance between the flanges. 55

4. An article of manufacture, comprising a spool with end flanges, a band of sensitized film and a band of protective paper interwound thereon, the paper band being 60 longer than the other band and its ends having side edges serrated, the width of the said ends being greater than the distance between the flanges. 65

5. A photographic film cartridge comprising a spool with end flanges, sensitized film and protective paper interwound thereon, the paper throughout its length having irregularly serrated side edges and being wider than the distance between the flanges. 70

6. A photographic film cartridge comprising a spool with end flanges, a band of photographic film and a band of protective paper interwound thereon, the paper band being longer than said film band and attached thereto and constituting end strips, the paper band throughout its length being wider than the distance between the flanges and having serrated side edges, and being of uniform thickness throughout. 75

7. A photographic film cartridge comprising coiled bands comprising sensitized material and protective material, a support therefor comprising spaced end flanges, said protective material being of uniform thickness and having its side edges serrated throughout its length. 80

Signed at Rochester, New York, this 21st day of July, 1921.

JOHN G. JONES.
